Attorney.

UNITED STATES PATENT OFFICE.

JULIUS C. MCCOY, OF ATHENS, WEST VIRGINIA.

CIGARETTE CONTAINER.

Application filed March 22, 1924, Serial No. 701,080.

To all whom it may concern:

Be it known that JULIUS C. McCoy, citizen of the United States, residing at Athens, in the county of Mercer and State of West Virginia, has invented certain new and useful Improvements in Cigarette Containers, of which the following is a specification, reference being had therein to the accompanying drawing.

10 This invention relates to certain improvements in paper containers of the dispensing slide type in which cigarettes are commonly packaged by manufacturers for sale to the public.

15 The purpose of the invention is to provide such a container with simple and inexpensive match holding means so designed and attached to the receptacle as to require no modification of the latter, aside from a slight increase in length.

20 Other purposes and advantages of the invention will be more readily understood from the following detailed description and accompanying drawings, in which—

25 Fig. 1 is a perspective view of a cigarette container or package of conventional form having my improved match holding means associated therewith.

30 Fig. 2 is a vertical longitudinal section through the container and match holding means as these parts appear when the container is fully closed.

35 Fig. 3 is a fragmentary plan view of the dispensing slide and match holding blanks assembled.

Fig. 4 is a sectional view on the line 4—4 of Fig. 3.

40 Fig. 5 is a fragmentary view of the container in side elevation, the slide being partly withdrawn from the casing and the flap of the slide open to expose the matches.

45 In the drawings, I have illustrated a conventional cardboard cigarette container which includes an outer casing 5, and a dispensing slide 6 positioned within said outer casing and provided with the usual closure flap 7 having a portion 7^a functioning to close the adjacent end of the slide and an extension 7^b functioning to close a portion of one side of the slide as is usual in containers of this type. For the purposes of my invention both the outer casing and slide are made slightly longer than is customary but are not otherwise changed from the conventional design. This slight increase in length is resorted to in order to afford suf-

ficient space within the slide 6 for the reception of my improved match holding means designated generally by the numeral 8 and positioned as best shown in Fig. 2 between the section 7^a of the closure flap 7 and the adjacent ends of the cigarettes 9.

As herein illustrated, the aforementioned match holding means consists of a substantially rectangular sheet of cardboard which is provided with parallel longitudinally extending score lines 10 dividing the sheet into three sections, respectively designated 10^a, 10^b and 10^c. A package of matches 11, of the so-called "safety" type is secured by a binding wire 12 to the central section 10^b of the sheet and a strip of match scratching material 13 is preferably interposed between the said wire and the matches to provide a convenient means for igniting the latter when detached. The match holding means, as thus completed, is attached to the slide 6 in the following manner: Section 10^a of the match holding sheet is glued or otherwise fastened to the portion 7^a of the closure flap 7 so as to move with and constitute a substantially integral member of the said flap. The sections 10^b and 10^c are bent, on the score lines 10, to form, with the section 10^a, a substantially rectangular casing enclosing the matches 11 on three sides, the top of the match casing in the closed position of the flap 7 being formed by the section 10^a, the bottom of the casing being formed by the section 10^c and one side of the casing being formed by the section 10^b. The ends of the casing thus formed are closed by the side walls of the slide 6 while the remaining side of the casing is closed by the extension 7^b of the closure flap. 95

When the cigarette container is fully closed, the sections 10^a, 10^b and 10^c of the match casing are disposed, as shown in Fig. 2, but when the closure flap 7 is moved to open position, the section 10^a, moving with the flap portion 7^a, will function to elevate the sections 10^b, 10^c and the matches 11 above and to one side of the adjacent ends of the cigarettes 9 so that the latter may be conveniently withdrawn from the casing. 105 The position of the parts, in the open position of the container, is clearly illustrated in Fig. 5.

While in the foregoing I have disclosed what I now consider to be the preferred embodiment of my invention, it is to be understood that various changes may be resorted

to within the scope and spirit of the appended claim.

What I claim as new is:

A cigarette container comprising an outer casing, a dispensing slide positioned in said casing and provided with a flap having a main portion adapted to close one end of the slide and an extension portion adapted to partially close one side of the slide, a strip of cardboard bent upon itself to provide a match housing having top and bottom walls and a side wall, said top wall being flatly engaged with the inner side of the first men-

tioned portion of the flap and permanently secured thereto, and matches secured to and carried by the side wall of the housing, said housing being normally positioned between the first mentioned portion of the flap and the adjacent ends of the cigarettes and being so joined to the flap as to move with the latter to a cigarette exposing position.

In testimony whereof I hereunto affix my signature.

JULIUS C. McCOY.
